[57] CLAIM

I claim the ornamental design for a paper clock, as shown.

DESCRIPTION

FIG. 1 is a perspective view of the paper clock;
FIG. 2 is a top plan view thereof;
FIG. 3 is a bottom plan view thereof;
FIG. 4 is a right side elevational view, the left side being a
mirror image thereof;
FIG. 5 is a front elevational view thereof; and,
FIG. 6 is a rear elevational view thereof.
